Primary Examiner — Barbara Fox

(57) **CLAIM**

The ornamental design for the tablet personal computer, as shown.

DESCRIPTION

FIG. 1 is the perspective view of the front view of the tablet personal computer showing my new design;

FIG. 2 is the perspective view of the rear view thereof;

FIG. 3 is the front elevational view thereof;

FIG. 4 is the rear elevational view thereof;

FIG. 5 is the left side view thereof;

FIG. 6 is the right side view thereof;

FIG. 7 is the top plan view thereof; and,

FIG. 8 is the bottom plan view thereof.

1 Claim, 7 Drawing Sheets

Perspective View of Front Side

Front Elevation View

Fig.1 Perspective View of Front Side

Fig.2 Perspective View of Rear Side

Fig.3 Front Elevation View

Fig.4 Rear Elevational View

Fig.5 Left Side View

Fig.6 Right Side View

Fig.7 Top Plan View

Fig.8 Bottom Plan View
